UNITED STATES PATENT OFFICE.

RALPH K. THOMSON, OF SIOUX FALLS, SOUTH DAKOTA.

DESIGN FOR AN AUTOMOBILE SIDE CURTAIN.

57,746.

Specification for Design. Patented Apr. 26, 1921.

Application filed July 16, 1920. Serial No. 396,844. Term of patent 14 years.

To all whom it may concern:

Be it known that I, RALPH K. THOMSON, a citizen of the United States, residing at Sioux Falls, in the county of Minnehaha and State of South Dakota, have invented a new, original, and ornamental Design for Automobile Side Curtains, of which the following is a specification, reference being had to the accompanying drawing, forming part thereof.

The figure is an elevation of an automobile side curtain, showing my new design.

I claim:

The ornamental design for an automobile side curtain, as shown.

RALPH K. THOMSON.
